CIRCUIT CONTROLLER

Herbert L. Bone, Forest Hills, William E. Smith, Pittsburgh, and Robert A. Woods, Swissvale, Pa., assignors to The Union Switch & Signal Company, Swissvale, Pa., a corporation of Pennsylvania

Application April 13, 1939, Serial No. 267,684

5 Claims. (Cl. 200—1)

Our invention relates to circuit controllers, and particularly to manually operable circuit controllers adapted to be assembled on a control panel as one of a group of similar units for controlling railway traffic controlling devices such as railway track switches or signals.

Circuit controllers embodying our invention are particularly well adapted for, but not limited thereto, use in railway traffic controlling systems such as, for example, the system disclosed and claimed in the application for Letters Patent, Serial No. 118,609, filed on December 31, 1936, by John M. Pelikan for Railway traffic controlling apparatus. Railway traffic controlling systems of the type disclosed in the aforesaid application Serial No. 118,609 have as an integral part thereof a control panel containing a diagram of the track layout and provided with a plurality of circuit controllers manually operable to two extreme positions and biased to an intermediate position, for controlling railway traffic controlling devices such as switches and signals. In systems of the type described, it has been found necessary to mount a large number of these controllers on a panel sufficiently small so as to enable the operator to see and operate each controller without shifting his position. It has also been found necessary that certain of the controllers be provided with means for indicating when the function which is to be effected by the controller is completed. It is readily apparent, therefore, that each controller and its associated indicator should occupy the least possible space, thereby permitting closer spacing of the controllers themselves and of the tracks shown in the track layout. Furthermore, it has been found necessary that each controller and associated indicator be readily accessible for repairs and replacements, thus requiring a unitary construction of the controller and indicator, whereby the unit as a whole is secured to the control panel but is readily removable therefrom with a minimum expenditure of time.

Accordingly, an object of our invention is the provision of novel and improved three-position circuit controllers which are manually operable to two extreme positions wherein in each position control contacts are selectively closed or opened, and which are biased to a position intermediate the two extreme positions.

Another object of our invention is the provision, in circuit controllers of the type described, of means for providing an indicator integral with such controller, in a manner such that the combination of the controller and its associated in-

dicator requires no more panel space than is usually required for a three-position circuit controller of usual construction.

A further object of our invention is the provision, in a circuit controller of the type described provided with an indicator, of novel and improved means for detachably securing the circuit controller and its associated indicator to the control panel, thereby permitting the detachment of a controller and its associated indicator from the control panel as a unit, and permitting the attachment of that unit for another unit of the same type, with the control panel.

Other objects and advantages of our invention will appear as the specification progresses.

Specifically, our invention relates to improvements in circuit controllers of the type described and claimed in an application for Letters Patent, Serial No. 123,014, filed January 29, 1937, by William E. Smith.

We shall describe two forms of circuit controllers embodying our invention, and shall then point out the novel features thereof in claims.

In the accompanying drawings, Fig. 1 is a top plan view showing one form of circuit controller embodying our invention. Fig. 2 is a vertical elevational view of the circuit controller shown in Fig. 1. Figs. 3 and 4 are each sectional views taken substantially on the lines 3—3 and 4—4, respectively, of Fig. 1. Fig. 5 is a top plan view, partially sectional, showing a modified form of the circuit controller shown in Fig. 1, and which modified form also embodies our invention. Fig. 6 is a vertical elevation view of the circuit controller shown in Fig. 5. Fig. 7 is a vertical elevation view showing a contact stack arrangement adapted for use with the circuit controller shown in Fig. 5.

Similar reference characters refer to similar parts in each of the several views.

Referring first to Figs. 1, 2 and 3, the reference character 8 designates a base member provided at its forward end with an upturned leg 9 having an opening 10, and provided on its rearward end with a spring member 11. A bearing member 12 is secured to the upturned leg 9 of member 8, and is provided with a bearing boss extending through the opening 10 in the leg 9. Slidably mounted in the bearing member 12 for longitudinal sliding movement is a tubular operating member 13, the outer end of which is formed with an integral button 14 adapted to be grasped for manually operating the member, and the inner end of which is threaded into a split collar 15 forming a part of a moulded cam mem-

ber 16 formed of insulating material. The split collar 15 is provided with two laterally extending lugs which when drawn together by a screw 17 threaded therein locks operating member 13 to collar 15. The operating member 13 normally occupies the position shown in the drawings, but is adapted to be at times pushed inwardly from its normal position to one extreme position and at other times to be pulled outwardly from its normal position to another extreme position. The operation of member 13 to its extreme positions is adapted to selectively govern the opening and closing of control contacts provided for the circuit controller, in a manner to be described presently.

The control contacts are provided for the circuit controller in a plurality of groups or stacks of contacts, here shown comprising two stacks in number, and designated by the reference characters S¹ and S². These stacks are both secured to an insulating member 18 which in turn is secured by rivets 19 to the base member 8, and are each provided with two rows of contacts (shown in part in Figs. 2 and 3), which are substantially similar in construction so that only the upper or top row of contacts of each stack is visible in Fig. 1. Furthermore, both stacks are constructed substantially similar to each other, so that the following description of the upper row of contacts of stack S¹ will suffice not only for the lower row of contacts of that stack, but will suffice also to describe both the upper and lower rows of contacts of stack S². Referring now to Fig. 1, wherein the upper row of contacts of stack S¹ may be best seen, this row comprises a plurality of superposed blocks 18a, 18b and 18c, formed of insulating material and attached to member 18 by means of screws 20. A first movable contact member 21 is clamped between block 18a and member 18, and is provided on its outer end with an inwardly projecting return bend, the function of which will be made clear presently. A first fixed contact finger 23 is clamped between the blocks 18a and 18b, and is retained in its normal position by a relatively stiff metallic stop 24 which is also clamped between the two blocks 18a and 18b. The contact fingers 21 and 23 are so adjusted that when no outward thrust is exerted upon movable finger 21, the parts will occupy the positions shown, in which position movable contact finger 21 is out of engagement with its associated fixed contact finger 23. The upper row of contacts of stack S¹ also is provided with a second fixed contact finger 26a clamped between insulating block 18c and member 18, and which finger constantly engages a projection provided on a contact member 32 carried by the cam member 16. The screws 20 are insulated from the various fingers and strips by means of insulated bushings which surround the screws. As was pointed out heretofore, the construction of each row of contact fingers of the stacks S¹ and S² is substantially similar to the construction just described for the upper row of contact fingers of stack S¹, so that the lower row of contact fingers of stack S¹ and the upper and lower rows of contact fingers of stack S² will be provided each with a first fixed contact finger and with a movable contact finger having a return bend, the above mentioned fingers of each row being so arranged that when no outward thrust is exerted upon its movable contact finger, that finger is out of engagement with its associated fixed contact finger. Furthermore, each row of contacts of stack S¹ is provided with a second fixed contact finger which

constantly engages an associated contact finger carried by cam member 16, and the upper row of contacts of stack S² (as shown in Fig. 1) also is provided with a second fixed contact finger constantly engaging an associated contact finger carried by cam member 16.

The operation of the control contacts is governed by cam surfaces 30 and 31 moulded on the insulating cam member 16, the cam surface 30 being adapted in the normal and extreme inward positions of the operating member 13, to exert an outward force on the return bends of the movable contact fingers of contact stack S², thereby operating those movable contact members into engagement with the associated fixed contact fingers. The other cam surface 31, provided on the cam 16, is adapted to exert an outward force on the return bends of the movable contact fingers of contact stack S¹, only in the extreme inward position of the operating member, thereby operating the movable contact fingers of contact stack S¹ (as for example contact finger 21) into engagement with the associated fixed contact fingers (contact finger 23 engaging its associated contact finger 21 in this position of the member 13). From the foregoing, it is obvious that when operating member 13 is in its extreme outward position, the contacts of each stack controlled thereby are open; when operating member 13 is in its normal position, the contacts of one stack S¹ are open and the contacts of the other stack S² are closed; and when operating member 13 is in its extreme inward position, the contacts of each stack are closed. It follows, therefore, that cam member 16 selectively opens or closes the control contacts provided for the circuit controller in accordance with the position of operating member 13. It is to be understood, of course, that the specific contact stack arrangement may be varied to best suit the contact engagement required for each specific application of the circuit controller.

As was pointed out heretofore, cam member 16 is also provided with contact members such as contact members 32 and 33 shown in Fig. 1, which engage, at all positions of the operating member 13, the respective second fixed contact fingers provided for the rows of contacts of stacks S¹ and S². The functions of the contacts constantly formed by the engagement of the contact fingers provided for member 16 with the second fixed contact fingers of stacks S¹ and S² will presently be made clear.

The operating member 13 and the cam member 16 are each provided with means cooperating with each other for displaying an indication. As here shown, member 13 is provided with a glass rod 35, lightly frosted on its extreme outer end, and extending through the operating member 60 from one end thereof to the other. The rod 35 is adapted to be illuminated at times by light rays from one or the other of a pair of indication lamps 36 and 37 contained within partitioned recesses 38 and 39 formed in cam member 16. The recesses 38 and 39 formed in member 16 are open at either end, the front end of each recess communicating with a common chamber 40 containing the inner end of the glass rod 35. The top and the other end of the recesses are enclosed 65 by a suitable plate 41 formed with a leg portion 42, the main portion of plate 41 covering the top of the recesses and being provided with suitable openings for ventilation thereof, while the leg portion 42 closes the other or rear end of the recesses and is provided with an opening for each

recess, into each opening of which a bayonet type lamp socket is soldered. Electrical contact is established with the indication lamps, when such lamps are inserted in the above mentioned sockets, by means of the previously mentioned contact members provided for the cam member 16, and the second fixed contact fingers provided for contact stacks S1 and S2, one contact formed thereby being interposed in the circuit for one lamp socket, another contact formed thereby being interposed in the circuit for the other lamp socket, and the other contact formed thereby being interposed in the common connection of both sockets. Since the control circuits for lamps 36 and 37 of the indication means form no part of the present invention, the circuits for the control thereof are omitted from the drawings for the sake of clearness.

In order to permit each lamp 36 or 37 to display a distinctive indication, the lamps may be provided with distinctively colored envelopes, or may be provided with clear glass envelopes and each be provided with a distinctively colored filter. As shown, the lamps 36 and 37 have clear glass envelopes and are provided with distinctively colored filters 43 and 44, one filter 43 being disposed in recess 38, and the other filter 44 being disposed in recess 39. These filters are preferably colored one green and one red, in accordance with the usual practice in the railway signaling art. It should be pointed out that when one lamp or the other of the pair of indication lamps is controlled to its illuminated condition, the glass rod 35 traversing the operating member 13 becomes illuminated to display at its frosted outer end the colored indication determined by the color or filter of the indication lamp then illuminated.

The leg 42 of cover plate 41 provided for the indication recesses 38 and 39 formed in the cam member 16, is provided with a laterally projecting extension 45, which is provided with an opening 46 having a larger diameter at one end thereof than at the other. The larger diametered portion of the opening 46 is adapted to receive the head of a pin 47 moulded integrally in the member 16, and the smaller diametered portion of the opening 46 is adapted to receive the shank of pin 47. When the cover member 41 is first positioned so that the head of pin 47 enters the larger diametered portion of opening 46, and the member is then moved so that the smaller diametered portion receives the shank portion of the pin, the head of pin 47 then engages the extension of member 41 to hold that member in its normal position wherein the recesses provided in member 16 are enclosed. It is readily apparent that by sliding cover member 41 so that the head of pin 47 can pass through the opening 46 in extension 45, the member 41 may then be removed from its normal position and may be raised to a position wherein the lamps 36 and 37 are accessible for inspection and replacement.

The base portion of the moulded cam member 16 is adapted to be engaged by L-shaped guide members 48 (see Fig. 4) secured to the base member 8, and which members serve to guide the sliding movement of member 16 in response to the operation of the operating member 13, in alignment with the axis of the operating member. These guiding members 48, which are secured to the base member 8 by means of the screws 49, by guiding the movement of the member 16 insure correct operation of the contact members of the contact stacks S1 and S2, and prevent any tendency of member 16 to bind, which tendency might

result if member 16 moves out of alignment with the axis of operating member 13.

Moulded integrally on each lateral side of cam member 16 is a V-shaped cam surface, the function of which will be pointed out presently.

The circuit controller and indicator are adapted to be assembled as a unit on a bracket member 50, which member is provided at its forward end with an opening 51 through which the outer end of operating member 13 may pass, and which opening serves to receive the boss provided on bearing member 12 of base member 8. The bracket 50 is further provided on its rearward end with a slot 52, which communicates with a hole 53 having a predetermined diameter. The slot 52 and the hole 53 provided in bracket 50 cooperate with means on base member 8 for detachably securing the circuit control unit to the bracket. As here shown, the base member 8 is provided with an opening 54 through which the shank 27 of a large headed locking pin 55 operates. The pin 55, which is secured to spring member 11 fastened to base member 8, extends downwardly through base member 8 and is provided with a shoulder 56 adjacent its head, the diameter of this shoulder being substantially larger than the diameter of the pin shank 27, and being substantially equal to the diameter of hole 53 provided in bracket 50. The shank 27 of pin 55 has a diameter substantially equaling the width of slot 52 formed in the bracket.

The bracket 50 is further provided on each side with spring biasing members 57 secured thereto, which members are provided with rollers 58 pivotally pinned to the extreme outward front portion of the members, and which, as will be described presently, cooperate with the V-shaped cam surfaces provided on member 16 for biasing operating member 13 to its normal or intermediate position. Each spring member 57 is provided with a stiffener member 59.

To assemble the circuit controller as a unit on its supporting bracket 50, operating member 13 is first aligned with the opening 51 formed in the forward portion of the bracket, and is then inserted into this opening. When the collar 56 of pin 55, provided for the base member 8, engages bracket member 50 to prevent further movement of operating member 13 into opening 51 of bracket 50, the spring member 11 may then be actuated to depress that spring member toward the base member 8, so that the shoulder portion 56 provided on the pin 55 is forced below the bracket 50, and the shank 27 of pin 55 is then received by slot 52 provided in the bracket. The unit may then be actuated in a forward direction, until the upturned leg 9 of base member 8 bears against the forward wall of bracket 50, and the boss provided for bearing member 12 is received by opening 51 in this bracket. At this position of base member 8, the spring member 11 may be released to actuate pin 55 secured thereto upwardly, so that the shoulder portion 56 of pin 55 is contained within the hole 53 of the bracket, and the head of the pin bears against the underside of the bracket, to which position the spring actuation of the member 11 biases the head. Also in this position of base member 8, the rollers 58 provided on the spring member 57 secured to bracket 50 enter the notches of the V-shaped cam surfaces moulded on member 16, so that the member 13 and member 16 secured thereto, are positioned as shown in the drawings.

In the normal position of operating member 13, as shown in Figs. 1, 2 and 3, the cam mem-

ber 16 governing the contacts of stacks S1 and S2 is also in its normal or intermediate position. When operating member 13 is pushed inwardly to move cam member 16 to its extreme inward position to selectively govern the control contacts as explained hereinbefore, the cam member 16, moving in response to the movement of member 13, actuates its forward V-shaped cam surfaces into engagement with the rollers 58 to force them apart against their spring bias. When the force exerted upon the operating member 13 to actuate it inwardly is removed, the rollers 58 in response to their spring bias return member 16 and operating member 13 to their normal positions, so that the control contacts governed thereby are restored to their normal positions. Likewise, when member 13 is pulled outwardly to actuate cam member 16 to its outward position wherein the contacts are selectively controlled as explained hereinbefore, the rollers 58 are forced apart by virtue of the action of the rearward surfaces of the V-shaped cam surfaces formed on member 16 so that when the operating member is released, the rollers 58 in response to their spring bias return cam member 16 and operating member 13 to their normal positions, and the contacts controlled by cam 16 also are restored to their normal positions.

It should be noted that a circuit controller constructed in accordance with our invention may be readily attached to or detached from a control panel. That is to say, since the circuit controller and indicator are incorporated into a single unit, the bracket 50 may be securely fixed to the control panel, and the controller unit may then be attached to, or detached from, the bracket by actuating spring member 11 to thereby actuate the locking pin 55 provided for the unit so that the shank 27 of pin 55 is received by the slot 52 provided in bracket 50, and then actuating the unit to attach or remove the unit, as the case may be. Preferably, as can be seen in Figs. 2 and 3, the pin 55 is disposed at a slight angle with respect to the opening 53 provided in bracket 50, so that in the event base member 8 of the controller unit moves rearward (as, for example, in response to the actuation of operating member 13 to its extreme inward position), the shoulder 56 will "bite" into the sidewalls of opening 53 provided in bracket 50 and the pin 55 will not be forced downward to a position wherein its shoulder clears the bracket 50. Since the pin 55 will not be moved downward under the above conditions, the engagement of shoulder 56 with bracket 50 retains the controller unit secured to its associated supporting bracket.

As shown, a spring clip 55a may also be provided for pin 55 and may be proportioned so that when fastened or clipped to the pin 55, the clip will prevent the movement of pin 55 to its full down position wherein its collar 56 clears the bracket 50, with the result that the controller unit may be removed from its associated supporting bracket only after the clip 55a has been removed from engagement with locking pin 55. It should be pointed out that, with the pin 55 having its shoulder 56 proportioned to be engaged by the sidewalls of hole 53 of bracket 50 in the manner previously described, the clip 55a need not necessarily be used to maintain the controller unit secured to its supporting bracket. However, the clip 55a may be employed as shown to further insure that under all conditions the controller unit can be removed

from its supporting bracket only after the clip is removed from its pin 55 to thereby permit the actuation of the pin to its full down position wherein shoulder 56 clears the supporting bracket 50.

One advantage of constructing a circuit controller in accordance with our invention, is that such construction enables a controller unit to be detachably secured to a control panel. This feature is particularly advantageous inasmuch as rapid interchange of circuit controllers can then be effected, whereby one controller unit may be removed from the panel and another unit placed in its bracket to function with the control apparatus of the system, while the removed unit is being inspected or repaired.

Another advantage of a circuit controller constructed in accordance with our invention is the provision of a moulded insulating cam member which combines in a single unit the multiple functions of controlling the operation of the contact members, of controlling the operation of the biasing means, and of providing individual compartments or recesses for each of the indication lamps and wherein each lamp is positioned. This construction permits a three-position circuit controller to be combined with a duplex light indicator in a unitary controller structure having the least possible external dimensions, and requiring no more panel space than is usually required for a three-position circuit controller of the ordinary construction.

In addition, the specific construction of the biasing means provided for the circuit controller is such that the lateral forces exerted upon the operating member 13, resulting from the biased engagement of the rollers 58 with the V-shaped cam surfaces formed on the member 16, oppose and balance each other so that the operating member 13 is maintained in axial alignment with its bearing 12, and is free to operate within its bearing without any tendency of the member to bind due to an unbalanced force being exerted thereon.

Referring now to Figs. 5 and 6, a second form of circuit controller embodying our invention as shown comprises a supporting bracket 60 having an upturned leg at either end, the forward leg 61 being provided with an opening 62 threaded to receive a bearing member 63, and the rearward leg 64 being provided with an opening 65 in axial alignment with forward opening 62. An operating member is mounted in bearing 63 and in opening 65 for longitudinal sliding movement between two positions. The operating member comprises a cylindrically formed rod 66 having its rearward end slidably mounted in opening 65 of rear bracket leg 64, and provided on its forward end (see Fig. 5) with a threaded stud engaged by an internally threaded opening provided in a sleeve member 67. The parts are so proportioned that with bearing 63 threaded into opening 62 of bracket leg 61, and with rod 66 having its one end mounted in opening 65 of leg 64, the sleeve 67 when threaded onto rod 66 is mounted in bearing 63, so that the operating member formed by the cooperation of sleeve 67 with rod 66 is mounted for longitudinal sliding movement.

The operating member normally occupies its normal position as shown in Figs. 5 and 6, and is adapted at times to be pushed inwardly from its normal position to one extreme position and at other times to be pulled outwardly from its normal position to another extreme position.

The movement of the operating member in each longitudinal direction is limited by shoulders formed on rod 66, the shoulders being so arranged as to permit a predetermined movement in either direction before the shoulders engage the rear face of bearing 63 or the rear leg of bracket 60, as the case may be. The movement of the operating member between its two extreme positions is adapted to selectively operate control contacts provided for the circuit controller, in a manner to be explained in detail presently. As shown, sleeve 67 is provided with an integral button adapted to be grasped so that the operating member may be readily operated between its two extreme positions.

The operation of the control contacts is governed by a single moulded cam member 68 formed of insulating material. Cam 68 is secured to rod 66, preferably by being moulded thereon, and is provided on either lateral side with a V-shaped notch. The cam 68 is further provided on its upper side with an inverted V-shaped cam. The function of the V-shaped notches and cam provided on cam member 68 will be pointed out presently.

An insulating member 69 is secured to the rearward leg 64 of the bracket 60 by means of screws 70. Clamped between the member 69 and bracket leg 64 are a pair of spring biasing members 71, one for each side of the moulded member 68, and which spring members are provided on their outer sprung ends with pivotally arranged rollers 72. The rollers 72 are biased by virtue of their attached spring members 71 into the notches of the V-shaped cam surfaces formed on either lateral side of the member 68, and thus serve to bias member 68 to a normal position intermediate its two extreme positions.

The member 69 supports control contacts provided for the circuit controller in two groups or stacks S3 and S4. Stack S3 is shown in Fig. 6 and comprises a plurality of superposed insulating blocks 73a, 73b, 73c, and 73d, which are secured to member 69 by insulated screws 74. A movable contact finger 75 is clamped between block 73a and member 69 together with a metallic stop 76 adapted to prevent downward movement of the finger, and is provided at its outer end with a bend 77 adapted to be engaged by the rearward cam surface of the inverted V-shaped cam formed on member 68. The bend 77 of this contact finger 75 is also provided with an upwardly projecting insulating block 78. A fixed contact finger 79 is clamped between blocks 73a, and 73b together with a fixed metallic stop 81, and a second fixed contact finger 80 is clamped between blocks 73c and 73d together with another fixed metallic stop 82. A second movable contact finger 83 is clamped between the blocks 73b and 73c, and is provided with an integral extension engageable by the insulated block 78 carried by the bend 77 formed in the outer end of the first movable contact finger 75. Normally, the contacts of stack S3 are in the position illustrated in Fig. 6, wherein contact fingers 75 and 83 are out of engagement with contact fingers 79 and 80, respectively. When operating member 66 is actuated to move cam member 68 formed thereon to its inward position, the rearward cam surface of cam 68 engages the bend 77 formed on contact finger 75 to actuate that finger upwardly and into engagement with contact finger 79, and the insulated block 78 carried by contact finger 75 actuates contact finger 83 upwardly into engagement with contact finger 80. Also 75

in this inward position of cam member 68, the rollers 72 are forced apart by the forward cam surfaces of the V-shaped notches formed in the lateral sides of member 68, so that the rollers 5 exert lateral forces upon the cam surfaces sufficient, when the force actuating operating member 66 inwardly is removed, to return cam member 68 inwardly to their normal positions, wherein the rollers 72 engage the 10 notches of the V-shaped cam surfaces.

Contact stack S4 is shown in Fig. 7 and comprises a plurality of superposed insulating blocks 84a, 84b and 84c secured to member 69 by means of the insulated screws 74. A movable contact finger 85 is clamped between blocks 84a and 84b, and is provided at its outer end with a return bend 86 adapted to be engaged by the forward cam surface of the inverted V-shaped cam formed on member 68. The contact finger 85 15 normally engages a fixed contact finger 87, which is clamped between block 69 and block 84c, and which is provided with a relatively stiff metallic stop 88 clamped similarly with its contact finger. A second fixed contact finger 89, provided with 20 a metallic stop 90, is clamped between the blocks 84b and 84c and is adapted to be engaged by contact finger 85 when return bend 86 of the latter finger is engaged by the forward cam surface of member 68. Thus with cam member 68 25 in its normal position, contact finger 85 engages contact finger 87, but when operating member 66 is pulled outwardly so that cam member 68 is moved to its outer position, the forward cam surface of member 68 engages the return bend 30 35 86 formed on contact finger 85 to force that finger upwardly out of engagement with contact finger 87 and into engagement with contact finger 89. In this position of cam member 68, the rollers 72 are engaged by the rearward cam surfaces of the V-shaped notches formed in the lateral sides of member 68 and are forced apart under spring tension so that when the force actuating operating member 66 is removed, the rollers 40 45 50 55 60 65 70 75 80 85 90 act upon the rearward cam surfaces of the V-shaped notches to return cam member 68 and operating member 66 to their normal positions wherein rollers 72 engage the notches of the V-shaped surfaces formed on the lateral sides of cam member 68. It is understood, of course, that the contact stock arrangement of stacks S3 and S4 may be varied to best suit the particular contact engagement required for each specific application of the circuit controller.

As indicated in Fig. 6, a circuit controller constructed in the manner just described may readily be mounted upon a control panel. To mount the controller on a panel, the panel is provided with an opening adapted to receive the threaded boss of bearing member 63, and the sleeve 67 is removed from engagement with rod 66 so that the circuit controller may be positioned with its forward bracket leg 61 engaging the rear face of the panel. The opening 62 of leg 61 then is aligned with the panel opening so that bearing 63 may be threaded through the panel opening into opening 62 of bracket leg 61, whereupon the bearing when tightened secures the controller to the panel. The sleeve 67 then may be threaded onto rod 66, thereby forming the operating member of the controller and completing its assembly upon the panel.

From the foregoing description, it can be seen that we have provided a three-position circuit controller normally biased to an intermediate position by means of opposing, balanced lateral

forces. It is readily apparent, therefore, that since no unbalanced forces are exerted upon the movable operating member controlling the control contacts, the biasing forces act both to return the operating member to its normal position and to hold that member in its axial alignment, thereby preventing any tendency of the member to bind during operation.

Although we have herein shown and described only two forms of circuit controllers embodying our invention, it is understood that various changes and modifications may be made therein within the scope of the appended claims without departing from the spirit and scope of our invention.

Having thus described our invention, what we claim is:

1. In a detachable panel mounted circuit controller, in combination, a bracket formed on one end with an upturned leg adapted to be secured to the rear face of a control panel and having an opening which aligns with an opening in said panel, a base member, means for detachably securing said base member to said bracket, an operating member, a bearing member secured to said base member in axial alignment with said openings in said panel and bracket for mounting said operating member for longitudinal sliding movement between two extreme positions, said operating member projecting through said openings in said panel and bracket to the front face of said panel, contacts secured to said base member and cooperating with said operating member for selective operation in accordance with the position of said operating member, and means secured to said bracket and cooperating with said operating member for biasing said operating member to a position intermediate its two extreme positions.

2. In a detachable panel mounted circuit controller, in combination, a bracket formed on one end with an upturned leg adapted to be secured to the rear face of a control panel and having an opening which aligns with an opening in said panel, a base member, means for detachably securing said base member to said bracket, an operating member, a bearing member secured to said base member in axial alignment with said openings in said panel and bracket for mounting said operating member for longitudinal sliding movement between two extreme positions, said operating member projecting through said openings in said panel and bracket to the front face of said panel, a moulded insulating cam member secured to said operating member and provided with operating cam surfaces and with biasing cam surfaces, contacts secured to said base member and cooperating with the operating cam surfaces of said cam for selective operation in accordance with the position of said operating member, and spring biasing members secured to said bracket and cooperating with the biasing cam surfaces of said cam for biasing said operating member to a position intermediate its two extreme positions.

3. In a detachable panel mounted circuit controller, in combination, a bracket formed on one end with an upturned leg adapted to be secured to the rear face of a control panel and having an opening which aligns with an opening in said panel, a base member secured to said bracket, an operating member, a bearing member secured to

said base member in axial alignment with said openings in said panel and bracket for mounting said operating member for longitudinal sliding movement between two extreme positions, said operating member projecting through said openings in said panel and bracket to the front face of said panel, a moulded insulating cam member secured to said operating member and provided on each lateral side with V-shaped biasing cam surfaces, said cam member also being provided with operating cam surfaces, contacts secured to said base member and cooperating with the operating cam surfaces of said cam for selective operation in accordance with the position of said operating member, and spring biasing members secured to said bracket one for each lateral side of said cam member and cooperating with the V-shaped biasing cam surfaces of said cam for biasing said operating member to a position intermediate its two extreme positions.

4. In a detachable panel mounted circuit controller, in combination, a bracket formed on one end with an upturned leg adapted to be secured to the rear face of a control panel and having an opening which aligns with an opening in said panel, a base member secured to said bracket, an operating member, a bearing member secured to said base member in axial alignment with said openings in said panel and bracket for mounting said operating member for longitudinal sliding movement between two extreme positions, said operating member projecting through said openings in said panel and bracket to the front face of said panel, a moulded insulating cam member secured to said operating member and provided on each lateral side with V-shaped biasing cam surfaces, said cam member also being provided with operating cam surfaces, contacts secured to said base member and cooperating with the operating cam surfaces of said cam for selective operation in accordance with the position of said operating member, and spring biasing members secured to said bracket one for each lateral side of said cam member, said spring biasing members being so disposed with relation to the V-shaped cam surfaces of said cam as to bias said operating member to a position intermediate its two extreme positions by virtue of equal opposing forces which maintain said operating member in alignment with said bearing member.

5. In a push-pull circuit controller of the class wherein a base member detachably secured to a bracket member supports a set of contacts and also mounts for longitudinal sliding movement between two extreme positions an operating member which selectively operates said set of contacts, the combination with said operating member and with said bracket of a cam member secured to said operating member and having oppositely disposed V-shaped cam surfaces, and spring biasing members secured to said bracket and disposed one to engage each of said V-shaped biasing cam surfaces in such manner that said operating member is biased to a position intermediate its two extreme positions by opposed and balanced biasing forces.
